His Attorney.

UNITED STATES PATENT OFFICE

LESTER E. SPRAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

APPARATUS FOR THE CONTROL OF TRACK INDICATORS

Application filed July 11, 1928. Serial No. 291,791.

My invention relates to apparatus for the control of track indicators, that is, indicators located in a tower or other central office for repeating the operation of the track relays of a series of track sections.

One feature of my invention is the provision of means for operating a plurality of such indicators with a minimum number of line wires between the track and the tower.

I will describe two forms of apparatus embodying my invention, and will then point out the novel features thereof in claims.

In the accompanying drawing, Fig. 1 is a diagrammatic view showing one form of apparatus embodying my invention. Fig. 2 is a diagrammatic view showing a modified form of apparatus also embodying my invention.

Similar reference characters refer to similar parts in each of the views.

Referring first to Fig. 1, the reference characters 1 and 1^a designate the rails of a railway track, which track is divided into a plurality of sections A¹, A², A³ and A⁴. Each section is provided with a track circuit comprising a track battery 3, and a track relay designated by the reference character T with a distinguishing exponent. Located in a tower or other central point are a plurality of indicators K¹, K², K³ and K⁴, which indicators are so controlled as to repeat the operations of the track relays T¹, T², T³ and T⁴, respectively. As here shown, each indicator is an electric lamp, but my invention is not limited to an indicator of this type.

The indicators K¹ and K² are included in two multiple branches of a circuit which comprises two line wires 7 and 8. This circuit is also provided with two multiple branches at the track, one of which branches includes contact 4 of track relay T¹, and the other of which branches includes contact 4 of track relay T². The tower branch including indicator K¹ is also provided with an inductance 5^a and a battery B, while the tower branch including indicator K² is also provided with a condenser 6^a and the secondary of a transformer C. The primary of this transformer is constantly supplied with alternating current from a source not shown in the drawing. The trackway branch including contact 4 of

track relay T¹ is also provided with an inductance 5, while the trackway branch including contact 4 of track relay T² is also provided with a condenser 6.

It will be seen from the foregoing that when both relays T¹ and T² are energized, indicator K¹ will be lighted by current from battery B which flows freely through inductances 5 and 5^a, whereas, indicator K² will be lighted by current from transformer C which flows freely through condensers 6 and 6^a. When a train enters section A², track relay T² will be de-energized, whereupon, indicator K² will be extinguished, because current from battery B cannot reach this indicator on account of condenser 6^a. Similarly, when a train enters section A¹, so that track relay T¹ becomes de-energized, indicator K¹ will be extinguished because alternating current from transformer C cannot reach this indicator on account of inductance 5^a.

The apparatus also includes a second circuit comprising line wires 8 and 9, and this second circuit is provided with two multiple tower branches including indicators K³ and K⁴, respectively. The second circuit is, likewise, provided with two trackway branches including contact 4 of track relays T³ and T⁴, respectively, the first branch being provided with an inductance 5 and the second branch with a condenser 6. The tower branch including indicator K³ is provided with an inductance 5^a and includes battery B, while the tower branch for indicator K⁴ is provided with a condenser 6^a and includes the secondary of transformer C. The operation of indicators K³ and K⁴ in response to occupancy of track sections A³ and A⁴, respectively, will be understood from the foregoing without further explanation.

Referring now to Fig. 2, the four indicators K¹, K², K³ and K⁴ are controlled by a single circuit comprising a pair of line wires 7 and 8, which circuit has four branches in the tower and four branches at the track. This circuit is supplied with alternating currents of four different frequencies by generators G¹, G², G³ and G⁴ included in the four tower branches respectively. The tower branch for indicator K¹ includes a tuning

device V^1 , comprising an inductance 10^a and a condenser 11^a , which tuning device is adjusted for resonance at the frequency of generator G^1 . The trackway branch which includes contact 4 of track relay T^1 is provided with a similar tuning device U^1 made up of an inductance 10 and a condenser 11 , this tuning device, likewise, being adjusted for resonance at the frequency of generator G^1 . The tuning device V^2 associated with indicator K^2 and the tuning device U^2 associated with track relay T^2 , are both adjusted for resonance at the frequency of generator G^2 . The tuning device V^3 associated with indicator K^3 , and the tuning device U^3 associated with track relay T^3 , are adjusted for resonance at the frequency of generator G^3 . The tuning device V^4 associated with indicator K^4 , and the tuning device U^4 associated with track relay T^4 , are adjusted for resonance at the frequency of generator G^4 .

When all four of the track sections are unoccupied, all four of the indicators K are lighted. When a train enters section A^4 , indicator K^4 is extinguished, because current from generator G^4 cannot pass through tuning devices U^1 , U^2 and U^3 . When a train enters section A^3 , indicator K^3 is extinguished, because current from generator G^3 cannot pass through tuning devices U^1 , U^2 and U^4 . For similar reasons, when a train enters section A^2 or A^1 , indicator K^2 or K^1 becomes extinguished.

As shown in Fig. 2, currents of different frequencies are furnished by individual generators, but I do not wish to be limited to this particular means for producing these currents.

It will be seen from the foregoing, that with the apparatus shown in Fig. 1, I am enabled to control four indicators with three line wires, six indicators with four line wires, etc., whereas, with the apparatus shown in Fig. 2, I am able to control any desired number of indicators over two line wires.

Although I have herein shown and described only two forms of apparatus embodying my invention, it is understood that various changes and modifications may be made therein within the scope of the appended claims without departing from the spirit and scope of my invention.

Having thus described my invention, what I claim is:

55 1. In combination, two sections of railway track, a track circuit including a track relay for each section, a tower indicator for each section, a circuit having two multiple branches at the tower and two multiple branches at the track, one of said track branches including a contact of one of said track relays and an inductance while the other track branch includes a contact of the other track relay and a condenser, one of said tower branches including one of said indicators and

an inductance while the other tower branch includes the other tower indicator and a condenser, a source of direct current included in one of said branches having an inductance, and a source of alternating current included in one of said branches having a condenser. 70

2. In combination, two sections of railway track, a track circuit including a track relay for each section, a tower indicator for each section, a circuit having two multiple branches at the tower and two multiple branches at the track, one of said track branches including a contact of one of said track relays and an inductance while the other track branch includes a contact of the other track relay and a condenser, one of said tower branches including one of said indicators and an inductance while the other tower branch includes the other tower indicator and a condenser, and means for supplying both direct and alternating current to said circuit. 75 80 85

3. In combination, two sections of railway track, a track circuit including a track relay for each section, a tower indicator for each section, a circuit having two multiple branches at the tower and two multiple branches at the track, one of said track branches including a contact of one of said track relays and the other of said track branches including a contact of the other track relay, the two tower branches including the two said indicators, respectively, means for supplying both direct and alternating current to said circuit, means for preventing direct current from passing through one track branch and one tower branch, and means for preventing alternating current from passing through the other track branch and the other tower branch. 90 95 100

In testimony whereof I affix my signature. 105
LESTER E. SPRAY.
